QUESTION AND ANSWER GAME BOARD

Robert E. Harris, 5366 N. Edgewood Drive,
Provo, Utah 84601

Filed Apr. 3, 1975, Ser. No. 564,961

Term of patent 14 years

Int. Cl. D21—01

U.S. Cl. D34—5 SS

FIG. 1

FIG. 2

FIG. 4

FIG. 3

FIG. 5

FIG. 1 is a perspective view of the entire question and answer game board embodying my new design;

FIG. 2 is a top plan view of the question and answer game board of FIG. 1;

FIG. 3 is a bottom view of the question and answer game board of FIG. 1;

FIG. 4 is a front elevational view of the question and answer game board of FIG. 1; and

FIG. 5 is a side elevational view of the question and answer game board of FIG. 1.

I claim:

The ornamental design for a question and answer game board, substantially as shown.
